UNITED STATES PATENT OFFICE.

JAMES H. PORTER AND EDWIN F. PORTER, OF BOSTON, MASSACHUSETTS.

SELF-LEVELING BERTH.

SPECIFICATION forming part of Letters Patent No. 278,732, dated June 5, 1883.

Application filed February 23, 1882. (No model.)

To all whom it may concern:

Be it known that we, JAMES H. PORTER and EDWIN F. PORTER, both of Boston, in the county of Suffolk and State of Massachusetts, have 5 invented certain Improvements in Self-Leveling Berths or Equivalent Structures, of which the following is a specification.

This invention relates to that class of self-leveling berths or equivalent structures in 10 which a beam is employed, which is pivoted to oscillate longitudinally, and to which the berth is pivoted, so that it can oscillate in a direction at right angles to the direction of oscillation of the beam, as shown, for example, 15 in Letters Patent of the United States granted to J. H. Porter, one of the present applicants, December 27, 1881.

Heretofore in this class of berths the pivoted beam has been supported only by its pivot. 20 Our invention has for its object, first, to furnish an additional support or supports for the beam, and thus diminish the wear and strain on the pivot thereof; and, secondly, to provide improved means for changing the center of 25 gravity of the berth, so as to compensate for any inequalities in the distribution of the contents of the berth.

To these ends our invention consists in the improvements which we will now proceed to 30 describe and claim.

Of the accompanying drawings, forming a part of this specification, Figure 1 represents a side elevation of a berth and supporting devices embodying our invention. Fig. 2 represents a section on line *x x*, Fig. 1. Fig. 3 represents a side elevation, showing a modification, and Fig. 4 represents an end elevation of Fig. 3.

The same letters of reference indicate the same parts in all the figures.

In the drawings, A represents the beam or frame which constitutes the direct support of the berth or structure B. Said frame is, in this instance, arranged mainly under the berth, and has a central upwardly-projecting arm or extension, 2, which is pivoted at C to a wall or other fixed support, and two upwardly-projecting arms, 3 3, to which the ends of the berth are pivoted at D D, the beam or frame being adapted to oscillate longitudinally and 45 laterally or at right angles to the direction of oscillation of the frame. The piv-

ots of the beam and berth are preferably provided with friction-rollers like those shown in the above-named patent, to which reference is made for a fuller description, and the pivots 55 of the berth are preferably provided with rubber or other springs to absorb the jars or vibrations of the vessel, as also shown in said patent.

E represents a fixed curved track attached to the deck, and located under the beam or frame A with its upper surface concentric with the pivot C of said frame.

F represents a curved portion rigidly attached to or forming a part of the frame A, said curved portion being concentric with the pivot C and 65 parallel with the track E. In the space between the curved portion F and track E are placed a series of friction-rollers, G, which directly support the curved portion F and allow the same to move freely back and forth when 70 the frame A oscillates. Said friction-rollers are preferably journaled in curved plates H H, which connect the rollers in a series and prevent them from being displaced. If desired, however, balls may be used instead of cylindrical rollers, the proximate surfaces of the track E and curved portion F being grooved to prevent the lateral displacement of the balls. 75 It will be observed that the curved track and rollers constitute an effective additional support for the beam or frame, sustaining nearly the entire weight of the frame and berth without interfering with or retarding the oscillations of the frame. If desired, two tracks E 80 may be provided, as shown in Fig. 4, the frame 85 being provided with two corresponding portions, F.

M represents a curved arm rigidly attached to the frame A, and preferably concentric with the pivot of the frame. On the arm M is a 90 weight, N, which is adapted to be adjusted on the arm, and provided with means for holding it in any position to which it may be adjusted. It will be seen that by changing the position of the weight N the center of gravity of the 95 frame and berth will be correspondingly changed, so that in case the contents of the berth are unevenly distributed, and the berth is inclined thereby, such uneven distribution can be compensated for and the berth leveled 100 by adjusting the weight.

It is obvious that a cattle-crib may be sup-

ported by the described means, the auxiliary supports being adapted to sustain a heavily-weighted structure. A section of floor of sufficient size to support a dining-table and a 5 number of people may be similarly supported.

We claim—

1. The combination of a frame carrying a berth suspended to swing laterally thereon, a stationary longitudinal curved track or bed 10 supporting the said frame, and pivoted to a stationary support at one side of the berth and at a point concentric with the circle with which said bed coincides, substantially as set forth.
2. The pivoted longitudinally swinging

frame supporting the laterally-swinging berth 15 or structure, and provided with an arm, M, and a weight, N, movable upon said arm, whereby the center of gravity of the berth or structure may be changed, as set forth.

In testimony whereof we have signed our 20 names to this specification, in the presence of two subscribing witnesses, this 18th day of February, 1882.

JAMES H. PORTER.
EDWIN F. PORTER.
